DISPLAY SHELF

Milton J. Chepp, Milwaukee, Raymond Irwin, Manitowoc, and Harold Auler, Milwaukee, Wis., assignors to Kayson, Inc., Manitowoc, Wis., a corporation of Wisconsin

Application March 29, 1954, Serial No. 29,716

Term of patent 14 years

(Cl. D80—9)

Fig. 1.

Fig. 2.

Fig. 3.

Fig. 4.

To all whom it may concern:

Be it known that we, Milton J. Chepp, Raymond Irwin, and Harold Auler, citizens of the United States, residing at Milwaukee, in the county of Milwaukee and State of Wisconsin; at Manitowoc, in the county of Manitowoc and State of Wisconsin; and Milwaukee, in the county of Milwaukee and State of Wisconsin, respectively, have invented a new, original, and ornamental Design for a Display Shelf, of which the following is a specification, reference being had to the accompanying drawings, forming a part thereof, and in which:

Figure 1 is a perspective view of a display shelf embodying our new design;

Figure 2 is a side view thereof;
Figure 3 is a front view of the display shelf; and
Figure 4 is a plan view thereof.

We claim:
The ornamental design for a display shelf, as shown.
